NICHOLAS S. VEDDER AND FRANCIS RITCHIE, OF TROY, NEW YORK, ASSIGNORS TO NICHOLAS S. VEDDER.

Design No. 3,332, dated January 5, 1869.

DESIGN FOR THE PLATES OF A STOVE.

The Schedule referred to in these Letters Patent and making part of the same.

To all whom it may concern:

Be it known that we, NICHOLAS S. VEDDER and FRANCIS RITCHIE, both of the city of Troy, in the county of Rensselaer, and State of New York, have jointly invented or produced a new and original Design for Stove-Plates, of which the following is a full and exact description, reference being had to the accompanying photographs, in which—

Figure 1 represents the main front plate, with two removable door-plates, and

Figure 2, a detached door-plate, on a larger scale.

Our new design for the main front plate A consists of the pairs of ornamented panels *b b b b*, the ornamented cross-bar *c c*, the ornamented top or cornice *d*, the scroll-like ornamentation *e e* and *f*, and tablets *g g* and *h*, all shaped and arranged as represented in fig. 1.

The design for the movable door-plates I and J on

the plate A consists of the centre ornament *k*, panel *l*, and mouldings *m m¹*, and the panel *n*, with ornamental border *o* and moulding *m²*, all shaped and disposed on the plates I and J, as shown in fig. 1; and

The design for the detached door-plate P consists of the series of ornamental belts *q r s r q*, shaped and arranged on a plain panel, *t*, so as to appear as represented in fig. 2.

What we claim as our invention or production, and desire to secure by Letters Patent, is—

The design for the stove-plates A, I, J, and P, as herein shown and described.

NICHOLAS S. VEDDER.
FRANCIS RITCHIE.
